HARRY H. HOFF AND FRANK E. TALLEUR, OF ST. LOUIS, MISSOURI.

SPARK-PLUG.

1,241,734.

Specification of Letters Patent.

Patented Oct. 2, 1917.

Application filed March 3, 1917. Serial No. 152,824.

To all whom it may concern:

Be it known that we, HARRY H. HOFF and FRANK E. TALLEUR, citizens of the United States, residing at St. Louis, State of Missouri, have invented certain new and useful Improvements in Spark-Plugs, of which the following is a full, clear, and exact description, reference being had to the accompanying drawings, forming a part hereof.

10 Our invention has relation to improvements in spark-plugs; and it consists in the novel features of construction more fully set forth in the specification and pointed out in the claim.

15 The object of the present invention is to provide a spark-plug for explosive or internal combustion engines which will embody in its construction suitable means for delivering to the combustion chamber the 20 desired quantity of inflammable liquid (gasolene or its equivalent) to produce a rich or priming mixture for starting purposes. It is understood by those skilled in the art, that the engine must, in the majority of cases be started with a rich or priming mixture, and when the engine is running, this mixture is changed to a lean mixture by the admission of the proper complement of air to the manifold or vacuum 25 chamber between the throttle of the carbureter and the engine. In some cases the necessary enriching of the starting mixture is effected by means of "priming devices" connected directly with the carbureter, but these often cause flooding of the carbureter.

30 By our invention the priming is done manually through the spark plug, the latter discharging the gasolene directly into the combustion chamber. There is thus no possibility of flooding the carbureter. The advantages of the invention will be apparent from the following detailed description in connection with the accompanying drawing in which—

35 Figure 1 represents an elevation of our improved spark-plug applied to an engine cylinder, the latter being shown in longitudinal middle section; Fig. 2 is an enlarged middle longitudinal section through the 40 body portion or socket of the spark-plug, the plug or insulating member being in elevation; and Fig. 3 is an elevation of the plug turned ninety degrees from the showing in Fig. 1.

45 Referring to the drawings, C, represents an engine cylinder, and P, the piston as well

understood in the art. The spark plug comprises a body portion or socket 1 terminating at one end in a reduced screw-threaded extension 2 for attaching to the engine cylinder. Formed on the inside of the socket is an annular shoulder s against which is seated the medial enlarged portion of the insulating member or plug 3, the upper reduced portion having passed over it a screw-threaded gland 4 which screws into the socket 1. The inner reduced portion of the insulating plug 3 enters the bore or gas chamber of the portion 2 of the socket, and is sufficiently spaced from the walls of said chamber to leave an annular clearance a around the plug. Leading from and communicating with, this clearance when the members 1, 3, and 4 are assembled, is the passage-way or bore w of the inclined tube 5, 50 the discharge end of said passage-way being below the shoulder s . Formed on the top wall of the tube 5 is an opening o which is normally closed by a screw-socket, sleeve, or cap-piece 6 terminating in a wing 7 for ready manipulation, the inner end of the socket when driven home bearing against the enlarged basal portion 5' of the tube 5.

55 In practice, whenever it is desired to introduce a quantity of gasolene into the combustion chamber B to insure a rich starting mixture, the socket 6 is unscrewed sufficiently to uncover the port or opening o (dotted position Fig. 2), whereupon the required quantity of the hydro-carbon is introduced 60 through the opening o into the bore or passage-way w , the liquid flowing down the passage-way w into the clearance a through the socket of the spark-plug into the chamber B. This done, the socket 6 is screwed 65 back to original position to cover the port o (Fig. 2) when by cranking the engine in the usual way, the engine will start, being supplied with the necessary quantity of priming mixture. We may of course depart in a 70 measure from the details here shown without in any wise departing from the spirit of our invention. Features shown but not alluded to are well understood in the art and require no description in the present 75 connection.

Having described our invention what we claim is:

80 In combination with a spark plug comprising an outer tubular socket and an inner 85 insulating plug shouldered thereto on the inside of the socket and extending beyond the 90

shoulder, said extension being spaced from the inner walls of the socket, an open-ended tube on the socket terminating in an enlarged basal portion, and disposed at an 5 incline to the axis of the socket and discharging into the bore of the socket below the shoulder aforesaid, the outer wall of the tube being screw-threaded, said screw-threaded portion having a peripheral opening 10 formed thereon, and an imperforate screw-cap passed over the screw-threaded

portion and operating to tightly seal said opening, said screw-cap being limited by the enlarged basal portion of the tube aforesaid.

In testimony whereof we affix our signatures in presence of two witnesses.

HARRY H. HOFF.
FRANK E. TALLEUR.
